[57] CLAIM

The ornamental design for a telephone booth, as shown and described.

DESCRIPTION

FIG. 1 is a perspective view of a telephone booth showing our new design;

FIG. 2 is a top plan view thereof;

FIG. 3 is a bottom plan view thereof;

FIG. 4 is a right side elevational as seen when in use; the left side being a mirror image thereof;

FIG. 5 is a front elevational view, the broken line showing of a telephone is for illustrative purposes only and forms no part of the claim design;

FIG. 6 is a rear elevational view thereof;

FIG. 7 is a cross sectional view taken along line 7—7 of FIG. 6; and,

FIG. 8 is a front elevational view without the broken line disclosure.

FIG. 1

FIG. 4

FIG. 6

FIG. 3

FIG. 2

FIG. 7

FIG. 5

FIG. 8
